UNITED STATES PATENT OFFICE.

LOUIS Y. McCONNELL AND CHARLES L. RAYMOND, OF ROCHESTER, NEW YORK.

CALCULATING-MACHINE.

SPECIFICATION forming part of Letters Patent No. 699,807, dated May 13, 1902.

Application filed June 27, 1901. Serial No. 66,233. (No model.)

To all whom it may concern:

Be it known that we, LOUIS Y. McCONNELL and CHARLES L. RAYMOND, citizens of the United States, and residents of Rochester, in the county of Monroe and State of New York, have invented certain new and useful Improvements in Calculating-Machines, of which the following is a specification.

This invention relates to calculating-machines. Its object is to simplify the construction of such machines and to produce an efficient, simple, and cheap mechanism.

It consists in the mechanism hereinafter described and claimed.

15 In the drawings, Figure 1 is a perspective view of a machine constructed according to this invention. Fig. 2 is a bottom plan view thereof, and Figs. 3 and 4 are views of details.

The machine has an outer casing A, having 20 a curved front a, a series of slots a', arranged, preferably, in parallel vertical planes, and a series of perforations a² for reading the totals added by the machine, and adjacent to each of the slots a' there is a series of digits, as shown. Within the case are a series of counting-wheels B', B², B³, B⁴, and B⁵, each of which has upon it a series of digits and a zero. In the present instance there are four such series on each wheel; but the numbers or series 25 of digits on each wheel may be any selected number, according to the size of the wheel. These counting-wheels are conveniently strung on the same shaft B⁰. Around the whole periphery of each counting-wheel and 30 adjacent to that portion which bears the series of digits is a series of teeth or ribs b, one for each digit upon the rim of the wheel. (See Fig. 3.) These ribs are used as finger-pieces or projections for moving the respective wheels, and the bottom of the slot a' constitutes a stop-point, beyond which the finger 35 cannot move in operating the wheel. The wheel B' relates to units, the wheel B² to tens, the wheel B³ to hundreds, the wheel B⁴ to thousands, and the wheel B⁵ to tens of thousands.

In order that the ribs b should be held in proper relation to the numerals of the case, a ratchet C is provided for each of the wheels 40 and adapted to engage in the depressions be-

tween adjacent ribs b, as shown in Fig. 3. The ratchet or dog C is held up to its position by a suitable spring c, Fig. 2, which presses the ratchet or dog and has a suitable bearing—as, for instance, the case. The series of 55 dogs C are strung upon a shaft C'.

Carrying mechanism is provided in this device consisting of a series of pinions b', b², b³, and b⁴, meshing with the ribs b upon the periphery of the wheels B' to B⁴, respectively, as 60 shown in Fig. 2. Whenever any one of these wheels is revolved, the pinion revolves with it. Each pinion is set upon a sleeve b⁰, (see Fig. 4,) and the whole series of pinions, with their sleeves, are strung upon a shaft B⁰, passing across the machine and having its ends supported in the case. The end of each sleeve b⁰ is notched or cut out, as shown in Fig. 4, thus forming two faces b¹⁰ b¹¹, and in the notch and between the two faces is a lug b¹² on a 65 block b¹³, also set on the shaft B⁰, which block bears a single spur-tooth b¹⁴. The spur b¹⁴ is adapted to engage the ribs b of the wheel of next higher denomination to that with which the pinion on its related sleeve b⁰ meshes, and 70 the single spur b¹⁴ is driven by the sleeve b⁰. The teeth on the pinions b' to b⁴ are of such number with relation to the number of teeth or ribs b upon the wheel with which it meshes that when one series of digits—upon the wheel 75 B', for instance—has passed the reading-point the pinion b' will be caused to make one revolution. Consequently in the present instance as there are four series of numerals upon each wheel there are forty teeth or ribs 80 upon the pinion b'. Hence when the reading on the units-wheel B' amounts to ten the tens-wheel B² will be moved one tooth-space and a digit will have been added to the reading on the tens-wheel, and so on through the 85 series. When, therefore, the pinion b' makes one revolution, the face b¹¹ of the sleeve b⁰ presses against the lug b¹² of the block b¹³ and will cause the single tooth to engage a rib b on the wheel B² and will advance said 90 wheel one tooth-space. The wheel B² will not move again until the pinion b' has made one complete revolution and the tooth b¹⁴ has again reached its engaging position. It is 95 necessary, however, to be able to rotate the 100

counting-wheel of a higher denomination without operating the carrying mechanism or counting-wheel of any lower denomination, and for this purpose there is a loose movement between the block b^{13} and the pinion b' of the next lower denomination. The distance between the faces b^{11} and b^{10} is such as to permit the movement of the block b^{13} by the wheel with which it is engaged, so as to turn said block until the tooth b^{14} disengages from the teeth or ribs b , and thus to permit the wheel with which the tooth b^{14} engages to move freely and without acting upon the spur-wheel b' ; but when the sleeve b^0 is again turned to the desired extent for a carrying operation the face b^{11} again engages the lug b^{12} and brings the tooth b^{14} into mesh with the wheel B^2 , causing the last-mentioned wheel to advance one tooth-space, as before.

It is obvious that the ribs b constitute gear-teeth for engagement with the carrying mechanism of the respective counting-wheels of the device.

Beginning with all the wheels set at zero, let us suppose that we wish to commence with the number "6." The finger is placed on the rib b of the wheel B' corresponding to the figure "6" of the units-column, and the wheel is then turned downward by the pressure of the finger until the finger stops against the lower edge of the wheel A^0 . It will then be found that the figure "6" will appear in the sight-opening a^3 of the units-column. If twenty is to be added, the finger is placed on the rib b of the wheel B^2 opposite the numeral "2" on the casing and is pressed downward until the finger stops on the bottom of the slot. If eighty-eight thousand is to be added to this amount, the finger is placed on the ribs b of the wheels B^4 and B^5 opposite to the numerals "8" on the casing and each wheel is turned by the finger in like manner. The reading will now be "88026" at the sight-openings a^2 . If now four is to be added on the units-wheel, the finger is placed on the rib opposite the numeral "4" and the wheel is moved downward until the finger stops on the bottom of the slot. This adds four tooth-spaces to the six as the machine is set, making the total tooth-spaces on the wheel that have been moved ten in number. If this motion of the wheel B' has occurred, it will have caused one complete revolution of its pinion b' , which will have moved the block b^{13} and will have caused the tooth b^{14} to engage the tens-wheel B^2 and to have moved it one tooth-space by the movement of the tooth and block. This will bring the figure "3" on the tens-wheel opposite the sight-opening. The same operation occurs when the sum of digits on the periphery of any wheel at the sight-opening equals ten. Let us assume, however, that any wheel stands at zero with the tooth b^{14} of its block engaged in a tooth-space on the periphery of the wheel. If this tooth were engaged with the pinion, a fresh move-

ment of the wheel with which the tooth b^{14} is engaged would cause a motion of the pinion; but in this invention a movement of the counting-wheel in the proper direction turns the block upon the shaft B^0 , and on account of the space between the faces b^{10} and b^{11} permits a backward movement of said block until the tooth disengages from the counting-wheel and the counting-wheel may continue its rotation disengaged from the tooth on the block; but just as soon as the carrying-pinion is rotated by its wheel the face b^{11} being always in fixed relation to the counting mechanism will engage the lug b^{12} and carry the block and its tooth into the proper position for turning the wheel to the next higher denomination to the extent necessary for a carrying operation.

What we claim is—

1. In a calculating-machine, a series of counting-wheels having teeth thereon, a series of pinions one engaging the teeth of each counting-wheel, said pinions having separated engaging faces b^{10} , b^{11} , a block for each pinion rotatable thereby and having a tooth b^{14} adapted to engage intermittently teeth of the wheel of the denomination next higher than that with which the pinion engages, a lug upon said block having a loose movement between said faces b^{10} and b^{11} and adapted on movement of the pinion in one direction to transmit a movement of one tooth-space to a wheel from the wheel of next lower denomination, said block being thereby capable of movement by the wheel of higher denomination to disengage said tooth b^{14} therefrom without moving the pinion, substantially as described. 85 90 95

2. In a calculating-machine, a series of counting-wheels having teeth thereon, a series of pinions one engaging the teeth of each counting-wheel, a block for each pinion and rotatable thereby and having a tooth adapted to engage intermittently the teeth of the wheel of the denomination next higher than that with which the pinion engages, means for driving said block by said pinion and having a loose movement as between the pinion and block whereby said block is so moved by the counting-wheel of the higher denomination as to disengage the tooth therefrom without moving the pinion, substantially as described. 105 110 115

3. In a calculating-machine, a series of counting-wheels having teeth thereon, a series of pinions one engaging the teeth of each counting-wheel, said pinions having extended hubs and sockets in said hubs forming engaging faces b^{10} , b^{11} , a block for each pinion and revolute thereby and having a tooth b^{14} adapted to engage the teeth of the wheel of the denomination next higher than that with which the pinion engages, a lug upon said block having a loose movement between said faces b^{10} , b^{11} , said pinions and blocks being strung on the same axle whereby on operat- 120 125 130

ing the wheel of lower denomination to a selected extent, the movement is transmitted through the block to the wheel of next higher denomination, and on operating said wheel 5 of next higher denomination the block turns and disengages said tooth from said wheel by the movement of the lug in said socket and

said pinion when moved, substantially as described.
